H. CAPPELLANTI

CIRCUIT CLOSER FOR ALARMS

Filed Nov. 28, 1923

UNITED STATES PATENT OFFICE.

HARRY CAPPELLANTI, OF MORGANTOWN, WEST VIRGINIA.

CIRCUIT CLOSER FOR ALARMS.

Application filed November 28, 1923. Serial No. 677,430.

To all whom it may concern:

Be it known that I, HARRY CAPPELLANTI, a citizen of the United States, residing at Morgantown, in the county of Monongalia 5 and State of West Virginia, have invented certain new and useful Improvements in Circuit Closers for Alarms, of which the following is a specification.

This invention relates to gas flow alarms 10 for automatically notifying a consumer when the supply of gas is shut off, and has particular reference to an improvement upon the gas flow alarm shown and described in my copending application, Serial No. 654-, 15 885, filed July 31, 1923.

It is well known that gas burners are often left lighted in buildings for illuminating or other purposes, and that for various reasons the flow or supply of gas is interrupted or cut off. When the supply of gas is thus interrupted, the burners are automatically extinguished, and when the supply of gas is continued again, the same escapes through the burners into the building 20 so as to result in a waste of gas, the occurrence of an objectionable odor therefrom, and even endangering of the lives of the persons in the building.

It is accordingly an object of the present 25 invention to provide approved means for immediately automatically notifying the occupants of a dwelling when this discontinuation of the supply of gas takes place, so that the burners may be turned off before 30 the supply of gas is again restored, and so that the escape of gas through the burners will be prevented.

Another object of the invention is to provide an alarm device which may be very 35 cheaply and easily installed without the requirement of special skill.

A further object of the invention is to provide an improved device of the above kind, which embraces the desired qualities 40 of simplicity and durability of construction as well as efficiency in operation.

Still another object of the invention is to provide a gas flow alarm of the above kind embodying electrical signalling means 45 having improved brake motor operated circuit closing means under the controlling influence of the gas pressure or flow.

Other objects will appear as the nature 50 of the invention is better understood, and the same consists in the novel form, combination, and arrangement of parts, herein-

after more fully described, shown in the accompanying drawings, and claimed:

In the drawing, wherein like reference characters indicate corresponding parts throughout the several views:

The figure is a view partly diagrammatic, with parts shown in vertical section and parts shown in elevation, of a gas line equipped with an alarm constructed in accordance with the present invention.

Referring more in detail to the drawings, 5 indicates an ordinary gas supply pipe through which the flow of gas is controlled by means of a valve, not shown. The outlet end of the pipe 5 is externally threaded and screwed within the branch 7 of a multi-way fitting which has a lateral branch 8 provided with means generally indicated at 70 9 for connection with a burner.

As shown clearly in Figure 1, the outlet end of the pipe 5 projects within the chamber of the fitting between the ports 7 and 8 and is open at both ends. A bell shaped piston 9^a is slidably mounted in the outlet end of the pipe 5 and the latter is provided with a lateral fork 10 adapted to be closed by the bell shaped piston 9^a when the latter is in its normal lowered position which it assumes by gravity when there is no gas 80 pressure in the supply pipe 5. Thus, when the gas pressure is shut off in the line 5, the piston 9^a assumes a closed position by gravity to close the port 10 and is adapted to be raised by said pressure within the pipe 5 90 when the same is resumed so as to uncover the port 10 and permit the free flow of gas through the fitting from the pipe 5 to the burner.

The multi-way fitting also includes a port 95 11, which is opposed to the port 7 and onto which is threaded the lower end member 12^a of a casing 12 of the alarm mechanism spring motor. The port 11 is closed by means of a plug 13 so as to prevent entrance of the gas into the casing 12, and this casing 12 contains a spring escapement 100 controlled motor generally indicated at M.

As shown in my above mentioned co-pending application, the spring motor embodies 105 a spring adapted to be wound by a suitable key, which spring is adapted to rotate a gear 15 that is operatively associated with an escapement wheel through a reduction gearing, generally indicated at 18. As is also 110 shown in my above mentioned co-pending application, the escapement wheel is asso-

ciated with an escapement lever in a well known manner, which escapement lever carries a fixed hammer 20, the free upper edge of which is provided with a head 21 and adapted to vibrate when released.

A rod 24 is rigidly attached to the piston 9^a and extends upwardly through the plug 13 where its upper end is impinged against the under side of an arm 25 that is rigid 10 with a lever L that normally engages the lower end portion of the hammer 20 for preventing swinging of the latter, when the piston 9^a, rod 24, and arm 25 are raised as shown by full lines in Figure 1. On the 15 other hand, should the pressure in the supply line 5, be discontinued for any reason, the piston 9^a will be allowed to lower by gravity for releasing the rod 24 from the arm 25 and thereby permitting the lever 19 20 to release from the hammer 20 so that the latter may freely vibrate under the actuating influence of the spring which operates the gearing 18. The construction thus far described is substantially the same as that 25 set forth in my above mentioned co-pending application.

The present invention embodies the use of a bracket composed of a tubular clamp member 26, having means, such as a screw 27 30 passing through ears 28 provided on the inner end of said clamp 26 for fastening the latter onto the outer end of the fitting upon which the casing 12 is mounted, the outer end of the clamp member 26 being provided 35 with a rigid upwardly extending tubular arm 29 of flattened form, as shown clearly by comparison of Figures 1, 2, and 4. The upper end of the arm 29 is closed by means 40 of a plate 30 formed of suitable insulating material and having a central plug portion 31 fitting into the upper end of said arm 29 as shown. This plate 30 has a pair of openings 32 in which are secured a pair of spaced binding posts 33 and 34 to which are 45 respectively attached the wires 35 and 36. Wire 35 connects to a terminal 37 of a suitable step-down transformer 38, the other terminal of which is indicated at 39 and is connected by means of a wire 40 with one 50 terminal 41 of an electric bell 42 of conventional form embodying a resonant shell 43 adapted to be struck by a vibratory hammer 44. The other terminal 45 of the bell 42 is connected to the wire 36 and thus the 55 bell 42 and transformer 38 are electrically connected in series in a normally open circuit which may be closed by bridging the binding posts 33 and 34. The feed wires 46 of the transformer 38 may carry a suitable 60 plug for engagement in the socket of an ordinary house wiring system.

The hammer 20, lever L, arm 25, and rod 24 are located rearwardly of the motor M and the casing 12 is provided with a removable closure at the rear thereof for permit-

ting ready access to these parts mentioned as located rearwardly of said motor M.

An opening is provided in one side of the casing 12 in a horizontal plane above the cap 30, and in a vertical plane between the binding posts 33 and 34, and this side of the casing is formed with an outwardly extending lateral boss 47 that is hollow and surrounds said opening in the casing 12 and provides means for slidably carrying a horizontally movable plunger rod 48. As shown clearly in Figures 3 and 5, the bore of the boss 47 is of substantially oval form, and the plunger rod 48 is of similar cross section, so that rotation of the plunger rod 48 is prevented. The inner end of the plunger rod 48 is disposed in the path of the hammer head 41 and suitably fixed upon the outer edge of the plunger rod 48 is a contact bridging element 49 that is preferably formed of a strip of spring metal, and that is substantially U-shaped as shown clearly in Figure 6. The contact bridging member 49 has its central portion suitably secured to the outer end of the plunger rod 48 such as by means of soldering or the like, and the legs of said bridging member 49 are arranged in diverging relation and normally extended away from the sides of the plunger rod 48 as shown clearly in Figure 2. This allows the resilient legs of the bridging element 49 to be forced together as the same pass between the binding post or contact members 33 and 34 so as to effect a good electrical connection between said binding posts 33 and 34 when the plunger rod 48 is forced outwardly for closing the circuit including the transformer 38 and bell 42.

When the gas is under pressure in the supply pipe 5, the piston 9^a is raised to the full line position shown in Figure 1, so as to cause upward swinging movement of the arm 25, thereby tilting the lever L for holding the hammer 20 in the position shown by full lines in said Figure 1. The plunger rod 48 is manually forced into the casing 12 with its inner end in contact with the hammer 21 and with the bridging element 49 retracted from between the binding posts 33 and 34. As long as the pressure is sustained within the pipe 5, the parts remain in this position so that the circuit including the bell 42 is opened. On the other hand, should the pressure in the supply line 5 be discontinued for any reason, the piston 9^a will be allowed to lower by gravity for releasing the rod 24 from the arm 25 and thereby causing the lever L to be disengaged from the hammer 20, thus permitting said hammer to vibrate under the actuating influence of the spring operated gearing 18 that is escapement controlled as above mentioned. Upon outward movement of the hammer 20, the latter forces the plunger rod 48 outwardly so as to move the bridging element 49 into the space

between the binding posts 33 and 34 and into an engagement with adjacent sides of the latter. When this takes place, the posts 33 and 34 are effectively electrically connected so as to close the circuit including the bell 42 and to cause operation of the latter for immediately notifying occupants of the building that the supply of gas has been discontinued and that the burners in the building should be inspected and if any were lighted that they should be turned off. When this is done no gas will escape into the building upon the resumption of the supply of gas to the burners, the currents of which will cause the piston 9^a to again rise for engaging the rod 24 with the lever 25, and swinging the latter and the lever L for holding the hammer 20 against further operation in the position shown by full lines in Figure 1. When the hammer 20 is thus engaged by the lever L, the plunger 48 may be manually reset or forced inwardly of the casing 12 for bridging the circuit including the bell 42 so that further operation of said bell will not be had. From the above, it will be seen that the alarm will continue to ring until the plunger rod 48 is reset for thereby compelling attention to the alarm.

From the above description, it is believed that the construction and operation, as well as the advantages of the present invention will be readily understood and appreciated by those skilled in the art, it being noted that by reason of the use of the wires 35 and 36, the bell 42 may be placed at any desired point remote from the bracket 29 and casing 12 as found most desirable and convenient in use of devices of this character.

It will be understood that the wires 35 and 40 of the device may be connected to a battery in buildings where electric systems are not installed, in which case the transformer 36 will be eliminated.

What I claim as new is:

1. A device of the class described comprising a multi-way fitting having a supply pipe projecting into the interior of the same through one port thereof, the inner end of the supply pipe being further provided with a lateral discharge port, a piston slidable in the inner end of the supply pipe, a casing mounted upon the fitting and containing a spring operated escapement controlled vibratory hammer, a rod projecting upwardly from said piston into said casing, an arm pivoted in the casing and having a rigid lever engageable with the hammer for holding the latter against vibration when the piston is raised by pressure within said gas supply pipe, said piston and rod being adapted to normally lower under the influence of gravity when the supply of gas is discontinued in the supply line for permitting said arm to lower for moving the lever fixed thereto out of engagement with said hammer whereby

the latter will be allowed to vibrate under the action of said spring operated escapement controlled mechanism therefor, a bracket carried by the fitting and having a pair of spaced contacts, connected in a circuit including an electric bell, and means carried by the casing and operable by and upon vibration of the hammer for bridging said contacts to close said circuit. 70

2. A device of the class described comprising a multi-way fitting having a supply pipe projecting into the interior of the same through one part thereof, the inner end of the supply pipe being further provided with a lateral discharge port, a piston slidable in the inner end of the supply pipe, a casing mounted upon the fitting and containing a spring operated escapement controlled vibratory hammer, a rod projecting upwardly from said piston into said casing, an arm pivoted in the casing and having a rigid lever engageable with the hammer for holding the latter against vibration when the piston is raised by pressure within said gas supply pipe, said piston and rod being adapted to normally lower under the influence of gravity when the supply of gas is discontinued in the supply line for permitting said arm to lower for moving the lever fixed thereto out of engagement with said hammer whereby the latter will be allowed to vibrate under the action of said spring operated escapement controlled mechanism therefor, a bracket carried by the fitting and having a pair of spaced contacts, connected in a circuit including an electric bell and means carried by the casing and operable by and upon vibration of the hammer for bridging said contacts to close said circuit, said last named means comprising a horizontal longitudinally slid able plunger rod projecting through the casing in the path of the hammer, and a resilient bridging element secured to the outer end of the plunger element and movable between and into engagement with adjacent sides of said contacts. 95

3. A device of the class described comprising a multi-way fitting having a supply pipe projecting into the interior of the same through one port thereof, the inner end of the supply pipe being further provided with a lateral discharge port, a piston slidable in the inner end of the supply pipe, a casing mounted upon the fitting and containing a spring operated escapement controlled vibratory hammer, a rod projecting upwardly from said piston into said casing, an arm pivoted in the casing and having a rigid lever engageable with the hammer for holding the latter against vibration when the piston is raised by pressure within said gas supply pipe, said piston and rod being adapted to normally lower under the influence of gravity when the supply of gas is discontinued in the supply line for permitting said arm to lower for moving the lever fixed thereto out of engagement with said hammer whereby 115

mitting said arm to lower for moving the lever fixed thereto out of engagement with said hammer whereby the latter will be allowed to vibrate under the action of said 5 spring operated escapement controlled mechanism therefor, a bracket carried by the fitting and having a pair of spaced contacts, connected in a circuit including an electric bell, means carried by the casing and oper- 10 able by and upon vibration of the hammer for bridging said contacts to close said circuit, said brackets comprising a tubular clamping member for detachably fastening the bracket to the outer end of said fitting, 15 and an upstanding hollow arm rigid with the outer end of said tubular clamp, a plate of insulating material covering the upper end of said tubular arm and including a plug portion fitting into the latter, said contact comprising screw binding posts sup- 20 ported in spaced relation and projecting upwardly from said insulating cap.

4. A device of the class described in- 25 cluding a pair of contacts arranged in an electric circuit, a switch member operable to engage said contacts to close the circuit,

and means for operating said switch mem- 30 ber, having a spring operated escapement control vibratory hammer, adapted to en- gage and operate the switch member in the vibrating movement thereof, a holding mem- 35 ber adapted to engage said hammer and pre- vent vibration thereof, and a fluid flow op- erated means, for operating said holding lever.

5. A device of the class described in- 40 cluding a pair of contacts arranged in an electric circuit, a switch member operable to engage said contacts to close the circuit, and means for operating said switch mem- 45 ber having a spring operated escapement controlled vibratory hammer, adapted to en- gage and operate the switch member in the vibrating movement thereof, and a fluid flow operating means for controlling and pre- venting the vibration of said hammer and the operation of said switch member there- 50 by, under the action of the escapement con- trolled operating spring.

In testimony whereof I affix my signa- 55 ture.

HARRY CAPPELLANTI
